AUTOMATIC AIR CLAMP AND RELEASE FOR TUBULAR BENDERS

Application filed February 23, 1926. Serial No. 89,970.

This invention relates to the art of bending elongated metallic articles and is more particularly concerned with pipe bending apparatus of the rotating bending roll type.

6 One object of the invention is to construct a bending machine of the rotating bending roll type having means for automatically tripping both the article supporting and roll rotating means.

10 Another object is to construct apparatus of the class described having a single control for the means for actuating the article supporting means and the bending roll.

A further object is to construct apparatus 15 of the class described having a single control for connecting and disconnecting the sources of power with the article supporting and roll rotating means.

Other objects will appear and be pointed 20 out hereinafter.

In the drawings forming a part of this application—

Fig. 1 is a top plan view of one form of apparatus embodying our invention;

25 Fig. 2 is a front side elevation of the apparatus of Fig. 1;

Fig. 3 is a right side elevation of the apparatus of Fig. 1;

30 Figs. 4 and 5 are respectively longitudinal and transverse sectional views of the fluid control valve forming a part of the apparatus of Fig. 1; and

Fig. 6 is a fragmentary view of the left side of the device of Fig. 1.

35 The form of apparatus embodying our invention and herein illustrated and described is constructed to bend elongated metallic articles, more specifically pipe. It comprises a supporting structure 1 upon the top of which 40 is carried a substantially cylindrical housing 2 provided with a top plate or cover 3 upon which a rotatable bending roll or die 4 and a longitudinally slidable die or follower shoe holding member or keeper 5 are mounted.

45 The die members 4 and 5 are provided as shown with suitably formed recesses 6 and 7 to receive a substantially cylindrical pipe, the recess 7 in member 5 running from end to end of the die member and being substantially 50 straight, while the recess 6 in the member 4

is straight for a portion of its length and is then curved into semi-circular form about the curved part of the roll. A pipe to be bent is fitted between roll 4 and die 5 and is clamped to roll 4 by a clamping die or shoe 55 8 and clamp 9. A trip member 9^a attached to roll 4 has an inclined surface to engage with a trip device presently to be described.

The die member 5 is pressed toward the member 4 by apparatus conveniently carried 60 by the cover 3 on the side of the member 5 opposite the member 4. This mechanism comprises a combined cylinder and toggle frame 10 secured adjustably to the cover 3, as by cap screws 11 extending through elongated openings 11^a therein. When the cap screws 11 are loosened the member 10 may be adjusted toward or away from the die member 5 by the adjusting bolts 12 carried by a bracket 13 which is secured to the cover 77 3 as shown. A piston 14 fits slidably in the cylinder portion of the frame 10 and carries a connecting rod 15 which is joined to a wedge plate 16 carrying toggle links 17, two of which are connected by suitable pins 18 to the frame 10 and the other two of which are connected by similar pins 18^a to a movable keeper 19 provided with a plurality of recesses 20 to receive anti-friction rollers which project slidably beyond the edge of the keeper to engage with the back surface of die member 5. A spring 21 between the piston 14 and frame 10 serves to restore the piston to the position shown in Fig. 1 when the pressure in the cylinder is released.

85 The cylinder portion of the member 10 is closed by a cylinder head 22 through which a fluid pipe 23 opens, the said pipe leading to a control valve 24 which is provided with an inlet pipe 25 and an exhaust pipe 26. The valve 24 consists of a body member 27 provided with a cover 28 and has tapped openings 23^a, 25^a and 26^a to receive the pipes 23, 25 and 26, respectively. The member 27 is provided in the end opposite the opening 25^a 90 with a tapped opening 28^a to receive a packing nut 28 and a rod 29 connected to a slide valve 30 shaped to reciprocate in and cooperate with the member 27 to connect the openings 25^a and 23^a, or to connect the open- 95 100

ings 23^a and 26^a. The valve 30 may be formed from a single block of material recessed on one side as at 31 to form a passage connecting the openings 23^a and 26^a and on the other side with a recess 32 extending from end to end thereof to connect the openings 23^a and 25^a, when suitably positioned in the member 27. A collar 33 carried by the rod 29 serves to space the valve 30 from one end of the member 27, thereby preventing communication of the openings 25^a and 26^a. It will be noted by referring particularly to Figs. 4 and 5 that sufficient space is provided in the member 27 so that the valve 30 may be moved toward the intake end far enough to uncover the outlet to pipe 23. The rod 29 is connected by a link 34 attached to a hand lever 35 which is pivotally supported by a hanger 36 secured to the cylinder 2, preferably beneath the member 10.

The bending roll 4 is rotated by a shaft 37 connected at will by a clutch 38 to a ring gear 39 disposed within the cylinder 2 which gear meshes with a worm gear 40 carried by a shaft 41 which is mounted for rotational movement in bosses 42 on the cylinder 3. This shaft 41 carries a pulley 43 and a clutch 44. The clutch is actuated by a collar 45 having pins which engage in the bifurcated ends of yokes 47 attached to the one end of a crank arm lever 48. This lever 48 is pivoted on brackets 49 carried by an extension support 50 attached to the member 1. The other end of the lever 48 is pivotally connected to one end of the lever 35 as by an adjustable link 51. Movement of the lever 48 about its pivot in brackets 49 serves to slide the collar 45 lengthwise of shaft 41, thereby operatively connecting and disconnecting the power pulley 43 with shaft 41 and thus actuating gears 40, 39 and, when clutch 38 is in place, shaft 37 and bending roll 4. Lever arm 48, by reason of its connection with lever 35, is actuated simultaneously with movement of the lever 35 and, in this manner, whenever the slide 30 in the control valve 24 is actuated the shaft 41 is also actuated. From the foregoing description it will be understood that the movement of the single lever 35 not only permits actuation of the die member 5 toward the bending roll 4, but also causes rotation of the roll in one direction. The bending roll is preferably restored to its starting position by first disengagement of the clutch 38 on its shaft with the ring gear 39 and then manual rotation.

Means are provided for automatically tripping the mechanism for rotating the roll 4 and the mechanism for holding the die member 5 thereagainst. As illustrated, this means comprises a lever 52 pivotally supported by brackets 53 on top of cover 3, this lever bearing at one end a block 54 to be engaged on the underside thereof by the trip member 9^a which engagement raises the block 54 and

pivots the lever 52 about its support in the brackets 53. At the opposite end the arm 52 is connected to a crank 55 which in turn is keyed to a shaft 56 carried beneath the cover 3 in suitable bearing blocks 57. This shaft 56 carries another crank 55^a similar to crank 55 but connected to a link 58 which in turn is joined to a bent lever 59 carrying therein adjacent to the bend a roller 61 to rest on the top surface of the lever 48. The other end of the bent lever 59 is pivotally carried by brackets 60 secured to the member 1.

It will be understood that when the block 54 is raised, the resulting downward movement of the arm 52 is transmitted through the crank 55, shaft 56, crank 55^a and thence by way of link 58, lever 59 and roller 61 to arm 48, depressing the latter and raising the grip end of the lever 35 which carries upwardly with it rod 29 and slide 30. This movement of the slide connects the pipe 23 with the exhaust 26 relieving the pressure on wedge block 16 and keeper 19 and permitting die 5 to move away from the roll 4. Simultaneous with this downward movement of arm 48 the clutch on shaft 32 is moved to disconnect the driving pulley, thereby interrupting the driving of shaft 41. When clutch 38 is disengaged as by lever 62 the roll 4 may be manually restored to starting position after the clamp 9 has been disengaged and the bent pipe removed. This tripping action obviously may be accomplished simply by downward movement of the grip end of the lever 30, as will be understood by those skilled in the art.

Although the apparatus is shown as adjusted for making a right angle bend, it may be adjusted to trip after a smaller bend has been made simply by varying the position of the tripping mechanism including parts 9^a and/or 52, 53, 54 and 55 or by otherwise stopping the bending action when desired. In certain instances the parts 52, 53 and 54 may be connected to crank 55^b instead of 55, if desired.

Having thus described our invention so that those skilled in the art may be enabled to practice the same, what we desire to secure by Letters Patent is defined in what is claimed, it being understood that the foregoing detailed description has been given merely for the purpose of illustrating and not for limiting our invention. Changes in the apparatus described and not amounting to invention may be made without departing from the spirit of our invention.

What is claimed is—

1. Apparatus for bending elongated metallic articles comprising in combination, a rotatable bending roll, a follower shoe or die, a keeper operatively associated therewith and movable transversely of the axis of the article to be bent, and means having a single control for simultaneously actuating the keeper and rotating the roll.

2. Apparatus for bending elongated metallic articles comprising in combination, a rotatable bending roll, a follower shoe, a keeper operatively associated therewith and movable relative thereto, and means, including a pivoted lever, for actuating the keeper and for rotating the said roll. having a hand lever disposed closely adjacent to the said lever of the clutch means.
- In testimony whereof we hereunto affix our signatures this 11th day of February, 1926.
- HARRY E. HARVEY. 70
EARL K. HOLMES.
3. Apparatus for bending elongated metallic articles comprising in combination, a rotatable roll, a shoe operatively associated therewith and adapted to exert sidewise pressure against an article between the roll and shoe, means for rotating the roll, means for actuating the shoe, and a single control directly connected to each of said means for actuating the roll and shoe. 75
4. Apparatus for bending elongated metallic articles comprising in combination, a rotatable roll, a keeper operatively associated therewith, fluid pressure means for moving the keeper toward the roll, a fluid pressure control valve, positive driving means for rotating the roll, a plurality of pivoted levers operatively associated with each other for simultaneous movement and connected to the said valve and to said roll driving means to actuate the same in unison. 80
5. Apparatus for bending elongated metallic articles comprising in combination, a bending roll, a keeper operatively associated with the roll, means for supporting the said keeper including a toggle mechanism, a fluid pressed piston connected to the said mechanism and a valve for controlling the pressure of fluid on the piston, means for rotating the roll and means for simultaneously actuating the said valve and the said roll rotating means. 85
6. Apparatus for bending elongated metallic articles comprising in combination a rotatable bending roll, a follower shoe, a keeper movable relative to and adapted to exert pressure upon an article between the roll and shoe, and means including a tripping device for automatically interrupting the rotation of the roll and releasing the keeper from the follower shoe. 90
7. Apparatus for bending elongated metallic articles comprising in combination, a rotatable bending roll, a follower shoe, a keeper movable relative thereto and supporting the said shoe, a trip device operable by the bending roll, and means including a plurality of pivoted levers actuated by movement of the trip device for interrupting rotation of the roll and releasing the keeper. 95
8. Apparatus for bending elongated metallic articles comprising in combination, a bending roll, means for rotating the said roll including a clutch having a hand lever, a keeper operatively associated with the said roll, means for actuating the keeper, and means including a single control for actuating the roll and the keeper, the said means 100
